FIG-5-

UNITED STATES PATENT OFFICE

WILLIAM MILLER, OF RITZVILLE, WASHINGTON

DOOR-OPENING DEVICE

Application filed April 22, 1930. Serial No. 446,378.

This invention relates to devices for opening doors and more particularly to devices for opening doors of motor vehicles or the like.

An object of this invention is to provide a device of this character by which a door may be opened by a foot pedal or the like.

Another object of this invention is to provide a device which may be readily positioned within the frame of a door of a motor vehicle and which will not interfere with the mechanism for raising or lowering the glass positioned within the frame.

A further object of this invention is to provide in combination with a foot pedal, means for facilitating the opening of the door particularly where a door is liable to stick or bind within the frame.

The above and various other objects and advantages of this invention will in part be described in and in part be understood from the following detailed description of the present preferred embodiment, the same being illustrated in the accompanying drawing wherein:-

Figure 1 is a side elevation partly in section of a device constructed according to the preferred embodiment of this invention mounted on a vehicle;

Figure 2 is a perspective view of the tripping or operating member;

Figure 3 is a fragmentary sectional view partly in detail of a modification of the tripping member;

Figure 4 is a sectional view taken on the line 4-4 of Figure 1;

Figure 5 is a sectional view taken on the line 5-5 of Figure 1; and

Figure 6 is a fragmentary detail elevation partly in section of the connecting link.

Referring to the drawing wherein like numerals of reference designate corresponding parts throughout the several views, the numeral 10 designates generally a door opening or sash which may be of any size desired and which may be positioned in the frame of a motor vehicle or the like, and the numeral 11 designates generally a door frame which is hinged as at 12 to the sash 10. The door frame 11 may be provided with a slideable

glass 13 which is adapted to move longitudinally within the frame 11.

The door frame 11 is adapted to be held in closed position by a latch member 14 which is slidably mounted in the frame 11, the outer end of the latch being adapted to engage in the conventional keeper or the like 15 which is mounted in the door sash. The inner end of the keeper 14 is adapted to be slidably mounted in a block or the like 16, and is constantly urged by an expanding spring 17.

A knob or handle 18 may be pivotally mounted in the door frame 11, and the knob 18 may be provided with an angularly inclined portion 19 which is adapted to engage against a pin or lug 20 which is carried by the bolt 14 so that the bolt 14 may be moved longitudinally within the frame 11 and the block 16.

An equalizer 21 is secured intermediate the ends thereof as at 22 to the bolt 14 and extends upwardly through a slot or opening 23 in the door stile 24, the upwardly extending portion 25 of the equalizer providing a handle by means of which the bolt 14 may be moved horizontally within the door frame. The door frame 11 is also provided with an inwardly extending block or lug 26 which is adapted to contact with the equalizer 21 intermediate the ends thereof.

The lower end of the equalizer 21 is pivotally or rockably secured to a door opening member or plunger 27 by means of a bolt or the like 28 and if desired, the plunger 27 may be restricted as at 29 so as to rockably receive the bifurcated lower end portion 30 of the equalizer 21. The plunger 27 is adapted to have horizontal movement within the frame 11, and one end thereof is provided with an inclined portion 31 which is adapted to engage against an inclined plate 32 carried by the sash 10, the inclined portion 31 facilitating or forcing the door to move into opened position when the plunger 27 is moved toward the open end of the door.

A spring member 33 may be positioned about the plunger 27 intermediate the equalizer 21 and the free end of the door frame 11 so as to constantly urge the plunger inwardly of the door frame. The opposite end of

the plunger 27 extends outwardly of the frame as at 34, and the sash 10 is provided with a slotted portion 35 so as to loosely receive the extension 34.

5 A plunger engaging member 36 may be hinged to the door sash 10, the plunger engaging member 36 having a depending portion 37 which extends loosely within the slot 35 and is adapted to contact with the inner end 10 of the plunger 27. If desired, the plunger engaging member 36 may be mounted on the floor of the vehicle and a horizontally movable rod or extension 38 secured thereto and adapted for contact with the inner end 34 15 of the plunger 27 so that when the plunger engaging member 36 is rocked, the plunger 27 will be moved outwardly thereby forcing the inclined outer end 31 thereof against the inclined plate 32 carried by the door sash and 20 coaxially rocking the equalizer 21 and moving the door bolt 34 inwardly of the door frame so as to permit the door to swing on the hinges 12.

In the operation of this device, the door frame 11 may be closed in the conventional manner, the bolt 14 holding the door in closed position. When it is desired to open the door from the interior of the vehicle, the member 36 may be rocked thereby moving the plunger 27 horizontally within the frame 11 and causing the outer end thereof to strike the inclined plate 32. Cooperatively with the horizontal movement of the plunger 27, the equalizer or link member 21 will be rocked, the outer edge thereof striking the lug 26 and causing the upper end of the link to move inwardly of the frame and thereby carry therewith the door bolt 14, thus releasing the frame of the door and permitting the door to swing 40 into opened position.

If desired, the bolt 14 may be moved horizontally within the frame by grasping the handle 25 of the equalizer or link 21, or if a person on the outside of the vehicle desires 45 to enter, the handle 18 may be rocked thereby bringing the extension 19 into contact with the pin 20 on the bolt 14. It will be obvious that the movement of the door bolt by means of the handle 25 or the knob 18 will cause 50 the bolt to move independently of the plunger 27 inasmuch as the link or equalizer 21 will be rocked on the pivot 28. It will be noted from the foregoing that the door frame 11 may be swung into opened position from various 55 positions within or without the vehicle.

It will, of course, be understood that various changes and modifications may be made in the details of construction and design of the above specifically described embodiment 60 of this invention without departing from the spirit thereof, such changes and modifications being restricted only by the scope of the following claims.

What is claimed is:—

65 1. A door opening device of the character

described comprising a door bolt adapted to be mounted in a hollow door structure, means for slidably mounting the door bolt in the door frame, a door opening member slidably mounted within the door frame, link means 70 connecting the member with said door bolt, and rockable operating means engaging one end of the member for coaxially moving the member and the bolt within the door frame to unlock and open the door.

2. A door opening device of the character described comprising a door bolt adapted to be mounted in a hollow door structure, a horizontally movable door opening member, an equalizer hingedly connected at the opposite ends to said member and said door bolt, a lug mounted on the door frame and adapted for contact with said equalizer, and operating means engaging one end of the member for moving said member horizontally within the door frame to unlock and open the door.

3. A door opening device of the character described comprising in combination with a door frame, a latch bolt slidably mounted within the frame, a door opening plunger slidably mounted within the frame, an equalizer connected to said plunger and said latch bolt, a lug mounted on the frame and adapted for contact with said equalizer intermediate the ends thereof whereby to rock said equalizer upon movement of said plunger, said rocking movement of said equalizer coaxially moving said bolt, means for moving said plunger horizontally within the door frame and means mounted on the door sash 100 and adapted for engagement with one end of the plunger whereby to open the door coaxially with the inward movement of said latch bolt.

4. A door opening device of the character described comprising a horizontally movable latch bolt, yieldable means for constantly urging said latch bolt into locking position, a knob mounted on the door frame and adapted for contact with said bolt, a horizontally movable plunger mounted within the door frame, said plunger having an inclined outer end portion, link means connecting said plunger to said door bolt whereby to move said bolt cooperatively with the movement of said plunger, an inclined plate mounted on the door sash and adapted for engagement with the inclined outer end of said plunger, and means for moving said plunger horizontally within the door frame.

5. A door opening device of the character described comprising in combination with a door sash and frame, a slideable latch bolt mounted in the door frame, a horizontally movable plunger mounted in the door frame, equalizing means connected to said plunger and said door bolt, said plunger having an inclined outer end portion, an inclined plate member mounted on the door sash and adapted for contact with the inclined outer end of

said plunger, yieldable means mounted about said plunger and adapted to constantly urge said plunger inwardly of the door frame, and rockable means adapted to engage the inner 5 end of said plunger whereby to move the plunger horizontally within the frame and coactively move the door bolt, the horizontal movement of said plunger forcing the outer inclined end thereof to contact with the inclined 10 plate carried by the door sash whereby to facilitate opening of the door.

6. A door opening device of the character described comprising in combination with a hinged door, a horizontally movable latch 15 bolt mounted in the door, a horizontally movable plunger mounted in the door, equalizing means connected to said plunger and said door bolt, said equalizing means extending upwardly from said bolt whereby to provide an 20 inclined grasping member for manually operating said door bolt, resilient means mounted on said plunger and adapted to constantly urge said plunger inwardly of the door, a lug mounted in the door and positioned intermediate 25 the bolt and said plunger whereby to rock said equalizer upon movement of said plunger outwardly of the door, said door bolt being adapted for independent movement with respect to said plunger upon movement 30 of said hand grasping member, and means for moving said plunger horizontally within the door.

In testimony whereof I hereunto affix my signature.

35 WILLIAM MILLER.
